COMPARTMENTED PACKAGING TRAY

Carlo Caprioli, Montreal, Quebec, Canada, assignor to
Plastic Packaging Products Ltd., Montreal, Quebec,
Canada

Filed Nov. 7, 1962, Ser. No. 72,417

Claims priority, application Canada May 10, 1962

Term of patent 14 years

(Cl. D58—13)

The figure is a top perspective view of a compartmented packaging tray showing my new design.

The characteristic feature of my design resides in the continuous, vertically corrugated margin, vertically scalloped at the ends of the recessed, alternating wide and narrow transverse compartments, as shown.

I claim:

The ornamental design for a compartmented packaging tray, as shown and described.
